C. W. LARNER

VALVE

Filed Dec. 8, 1921

Inventor:
Chester W. Larner
by Edwards, Lager & Power
his attorney

UNITED STATES PATENT OFFICE.

CHESTER W. LARNER, OF PHILADELPHIA, PENNSYLVANIA, ASSIGNOR, BY DIRECT AND MESNE ASSIGNMENTS, TO THE WILLIAM CRAMP & SONS SHIP & ENGINE BUILDING COMPANY, A CORPORATION OF PENNSYLVANIA.

VALVE.

Application filed December 8, 1921. Serial No. 521,059.

To all whom it may concern:

Be it known that I, CHESTER W. LARNER, a citizen of the United States, residing at Philadelphia, in the county of Philadelphia and State of Pennsylvania, have invented certain new and useful Improvements in Valves, of which the following is a specification.

The present invention relates to cylinder and plunger valves opened and closed principally by the pressure of the fluid which flows through them.

Objects of the invention are first to provide for opening the valve under relatively low head and when arranged in vertical position and adapted to close downward; second, to provide improved means for opening and closing such a valve when arranged in any position; third, to provide for reducing the dead weight of the valve when in vertical position so that comparatively low upward pressure will satisfactorily open it, and fourth, to provide an improved valve of the general type recited.

The invention will be claimed at the end hereof, but will be first described in connection with the embodiments of it selected from other embodiments for the sake of illustration in the accompanying drawings, forming part hereof, and in which:

Fig. 1 is a vertical sectional view of a valve embodying the invention.

In the drawings 1, is a seat structure, 2, is a cylinder element spaced from the seat structure as by means of radial ribs 3, to provide a fluid way. The head 4, of the cylinder is closed. 16 is a plunger element having a pointed nose co-operating with the seat structure 1, to open and close the fluid way of the valve.

The plunger element 16 is formed with a differential portion providing an annular chamber A between the casing 1 and piston 22 for lifting pressure entering by leakage or through the ports 27. The pressure in the inner chamber is controlled by valve 19 and exhaust port 18 in the nose of the plunger, the pressure being supplied to this inner chamber by leakage for instance through bearing 23 around stem 20 of valve 19. To close the plunger stem 20 and valve 19 are lowered by any desired means such as a rack and pinion to close or restrict port 18 and

then pressure builds up in the inner chamber sufficient to overcome the pressure in annular chamber A. The plunger element 16 will follow closely the movement of the valve 19 for any tendency to overrun the downward movement of the valve will be checked by the resultant automatic opening of the port 18 and corresponding reduction in pressure in the inner chamber. Similarly in opening a permanent upward pressure tending to float the valve is afforded by annular chamber A and the interior pressure is reduced by lifting valve 19 and increasing the opening through the port 18.

The plunger element 16 thus tends to float open and is moved and held in any desired position by control of the downward or closing pressure which is normally exerted without mechanical effort and simply by adjustment of the valve 19 to vary the rate of the exhaust discharge through opening 18.

In addition to moving plunger 16 by means of the hydraulic pressure exerted upon it, plunger 16, may be moved mechanically by valve 19 pushing against its seat in the plunger element.

I claim:

In a hydraulic valve structure the combination with the vertical wall of a fluid way gradually tapering downward to form a valve seat, of a fixed cylinder supported from said wall, a vertically movable valve plunger sliding in said cylinder and having a piston portion between an inner chamber and a surrounding annular chamber A within the cylinder and a nose portion subjected to the floating action of vertically upward fluid-way pressure and tapered to form a smoothly contracting annular passage with the fluid way, wall and provide a region of permanently low pressure adjacent the end of said plunger, and means for reducing the interior pressure above the plunger to float it open to any desired position consisting of a single valve opening through the end of the plunger to the fluid way and means for controlling said opening to vary said interior pressure and move the valve to any position and hold it there solely by hydraulic pressure and without the exertion of mechanical force on the plunger.

CHESTER W. LARNER,
